(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of the claimed design;

FIG. 2 is a second image thereof; and,

FIG. 3 is a third image thereof.

The dashed broken lines in the figures show a display screen or portion thereof, and form no part of the claimed design. The dot-dash broken lines in the figures and the areas between the dot-dash broken lines and the dashed broken lines show portions of the animated graphical user interface that form no part of the claimed design.

The appearance of the animated image sequentially transitions between the images shown in FIGS. 1-3. The process or period in which one image transitions to another forms no part of the claimed design.
